COMBINATION UTILITY SINK CAN WASHER SANITIZER

Roy L. Emanuele, Massapequa, N.Y., assignor to Institutional Maintenance Corporation, Brooklyn, N.Y.

Filed July 27, 1970, Ser. No. 24,131

Term of patent 14 years

Int. Cl. D23—02

U.S. Cl. D23—50

FIG. 1

FIG. 2

FIG. 5

FIG. 6

FIG. 3

FIG. 7

FIG. 4

FIG. 1 is a perspective view of a combination utility sink can washer sanitizer showing my new design;

FIG. 2 is a top plan view thereof;

FIG. 3 is a front elevational view thereof;

FIG. 4 is a bottom plan view thereof;

FIG. 5 is a left side elevational view thereof;

FIG. 6 is a right side elevational view thereof; and

FIG. 7 is a rear elevational view thereof.

I claim:

The ornamental design for a combination utility sink can washer sanitizer, substantially as shown.
